(57) **CLAIM**

The ornamental design for a floor drain, as shown and described.

DESCRIPTION

FIG. 1 is the floor drain in an exploded view, showing my new design;

FIG. 2 is a front perspective view of the floor drain, shown fully assembled;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a rear perspective view thereof; and,

FIG. 9 is a bottom view thereof.

The broken lines depict portions of the floor drain that form no part of the claimed design.
